(57) **CLAIM**

The ornamental design for a handle for mesh basket, as shown and described.

DESCRIPTION

FIG. 1 is a front perspective view of a first embodiment of a handle for mesh basket showing our new design;

FIG. 2 is a front view thereof;

FIG. 3 is a left side view thereof, the right side being a mirror image;

FIG. 4 is a front perspective view of a second embodiment thereof;

FIG. 5 is a front view thereof;

FIG. 6 is a left side view thereof, the right side being a mirror image;

FIG. 7 is a front perspective view of a third embodiment thereof;

FIG. 8 is a front view thereof; and,

FIG. 9 is a left side view thereof, the right side being a mirror image.

The broken line showing of structural lines is included for the purpose of illustrating non-claimed subject matter and forms no part of the claimed design. The dash-dot broken lines represent an artificial boundary and form no part of the claimed design.
